UNITED STATES PATENT OFFICE.

SAMUEL R. AUKER, OF ALTOONA, PENNSYLVANIA.

COMBINED SHADE AND CURTAIN FIXTURE.

No. 843,658.

Specification of Letters Patent.

Patented Feb. 12, 1907.

Application filed June 5, 1906. Serial No. 320,321.

To all whom it may concern:

Be it known that I, SAMUEL R. AUKER, a citizen of the United States, residing at Altoona, in the county of Blair and State of Pennsylvania, have invented certain new and useful Improvement in Combined Shade and Curtain Fixtures, of which the following is a specification.

This invention relates to combination shade and curtain fixtures designed to be applied to a window-frame, comprising means for properly hanging the ordinary spring-controlled shade-roller and the pole for lace curtains.

To this end the invention contemplates a simple and practical construction of combined shade and curtain fixture embodying every adjustment necessary for adapting the fixture to varying lengths of shade-rollers and to different forms and sizes of window-frames. Also the invention has in view a novel and practical construction for permitting the lace-curtain holder to be hung at any desired distance from the window-frame, or, in other words, to maintain any relative distance desired between the window-shade and the lace curtain.

Another object of the invention is to provide a separable knockdown structure which can be readily set up and taken apart.

With these and many other objects in view, which will more readily appear as the nature of the invention is better understood, the same consists in the novel construction, combination, and arrangement of parts hereinafter more fully described, illustrated, and claimed.

The essential features of the invention involved in carrying out the foregoing objects are necessarily susceptible to structural change without departing from the scope of the invention; but a preferred embodiment of the latter is shown in the accompanying drawings, in which—

Figure 1 is a top plan view of a combined shade and curtain fixture embodying the present invention, the view also including the projected end elevation of the extensible supporting-bar. Fig. 2 is a front elevation of the fixture. Fig. 3 is an end view thereof. Fig. 4 is a large cross-sectional view on the line 4 4 of Fig. 2. Figs. 5, 6, and 7 are a series of elevations of the adjustable curtain-holder. Figs. 8, 9, and 10 are similar views of the hanger-bracket for the fixture. Figs.

11, 12, and 13 are similar views of the supplemental bracket-pieces for supporting the curtain-holders. Fig. 14 is a diagrammatic cross-sectional view on the line 14 14 of Fig. 1, showing the telescopic engagement between the parts 2 and 3 of the supporting-bar.

Like references designate corresponding parts in the several figures of the drawings.

The invention includes in its general organization an extensible supporting-bar, designated in its entirety by the numeral 1 and essentially consisting of a central sleeve-section 2 and the oppositely-arranged extension-sections 3, telescopically engaging the sleeve-section 2. Both the sleeve and end sections 2 and 3 consist of angled plates, or, in other words, are of an L shape in cross-section, as plainly shown in Figs. 1 and 14 of the drawings; but in order to provide for a telescopic engagement of the sleeve-section and the end sections the said sleeve-section is provided along its longitudinal edges with the inturned slide-flanges 4, which are slidably engaged by the edges of the sections 3, and the latter slidably register within the angle of the sleeve-section 2, so that the several sections constitute what has been termed an "extensible supporting-bar" 1, inasmuch as the end sections 3 are free to be slid in and out to vary the length of the supporting-bar to suit the width of the window-frame to which the fixture is applied. The said extensible supporting-bar 1 constitutes a carrying element for supporting and partially housing the shade-roller. To provide for this, the said supporting-bar has fitted to the outer ends of its end sections 3 the shade-roller brackets 5 and 6, respectively, which are provided with the usual slots and openings 7 and 8 to receive the opposite journal extremities of the shade-roller. By reason of this arrangement of the brackets 5 and 6 the shade-roller is partially housed beneath the upper horizontal flange of the supporting-bar 1, so that the roller is protected from dust that usually settles on the top thereof and frequently leaves a dirty streak, which appears upon the shade when drawn down.

The extensible supporting-bar 1 is properly supported in position through the medium of upright hanger-brackets 9, adapted to be arranged at opposite sides of the window-frame and which are provided with a plurality of keyhole-slots 10, adapted to be

detachably locked over the heads of supporting-screws screwed in the window-frame for holding the fixture in place.

Each upright hanger-bracket 9 is provided

- 5 at its outer side with an angled spring-holding clip 11, having a vertical member 12 and a horizontal member 13. The vertical flange of one of the end extension-sections 3 of the bar 1 is adapted to be inserted behind the
10 vertical member 12 of the clip 11, while the horizontal flange of said extension-section will rest on the horizontal member 13 of said clip. This provides a firm support for the supporting-bar, while at the same time admitting of lengthwise adjustment thereof and also of its ready removal.

- Each fixture-hanger bracket 9 is further provided at its upper end with a rest-socket 14, receiving the supporting-leg 15, bent
20 downwardly from one end of the supplemental bracket-piece 16, provided therein with a longitudinal play-slot 17, and at the end opposite the leg 15 with an upstanding keeper-lug 18. This lug is provided therein
25 with a tapering wedge opening 19, adapted to receive therein the adjustable holder-arm 20 for the lace-curtain pole. The holder-arm 20 is provided at its inner end with a headed slide-foot 21, engaging the slot 17,
30 and at its other end is provided with a pole-hook 21^a, in which rests the curtain-pole. In the outer side of the hook 21^a there is preferably mounted a retaining-screw 22 for securing the curtain-pole in place. The weight of
35 the curtain-pole on the holder-arms 20 serves to lock the same in the wedge openings 19. At the same time in setting up the fixture the curtain-holder arms 20 can be readily adjusted inward or outward.
40 Should the conditions of use require screwing or otherwise fastening the shade-roller brackets 5 and 6 directly to the window-jambs, thus obviating the use of the fixture-brackets 9, another feature of the invention
45 comes into use. That feature resides in the provision of spacing-bosses 23 on the outer sides of the brackets 5 and 6, and keeper-

slots 24 in the upper sides of the end sections 3 take the place of the sockets 14 of said fixture-brackets.

50

I claim—

1. A fixture of the class described comprising oppositely-arranged hanger-brackets each having a holding-clip and a socket at its upper end, a supporting-bar having its end portions adapted to fit over and engage behind said holding-clips, said supporting-bar carrying at the ends shade-roller brackets, a supplemental bracket-piece for each hanger-bracket having a supporting-leg at one end 55 for engagement with the socket of said bracket, and an adjustable curtain-holder arm slidably fitted to and adjustably connected with each of said bracket-pieces and provided at its outer end with a holder-hook 60 having retaining means.

2. A fixture of the class described comprising oppositely-arranged hanger-brackets each having an angled holding-clip and a socket at its upper end, an extensible supporting-bar having end sections adapted to fit over and engage behind said holding-clips, said end sections of the bar carrying shade-roller brackets, a supplemental bracket-piece 70 for each hanger-bracket having a longitudinal play-slot, a supporting-leg at one end for engagement with the socket of said hanger-bracket and at its opposite end provided with an upstanding keeper-lug having a wedge opening therein, and an adjustable curtain-holder arm extending through the opening of said keeper-lug and provided at its inner end with a downturned headed slide-foot engaging the play-slot of the bracket-piece, said holder-arm being provided at the 75 outer end with a holder-hook having a retaining-screw.

In testimony whereof I hereunto affix my signature in the presence of two witnesses.

SAMUEL R. AUKER.
